UNITED STATES PATENT OFFICE

2,141,160

DISPENSER

Samuel Bloomfield, Chicago, Ill.

Application May 21, 1938, Serial No. 209,310

6 Claims. (Cl. 221—62)

This invention relates broadly to receptacles, and more particularly to a receptacle especially adapted for dispensing granular and related substances such as sugar, one of the principal objects of the invention being the provision of a dispenser having an automatically opening closure means for a spout formation and operable, when the receptacle with which it is associated is tilted out of its normal position, to open so that the contents of the receptacle may flow freely therefrom.

Another object is the provision of a dispenser including an upright receptacle having a metal cap with a spout formation extruded therefrom and a gravity-operated closing flap for the spout which will open and close as the receptacle is tilted into and out of upright position.

Yet another object is the provision of an upright receptacle having a metal cap with a portion extruded to provide a substantially conical or sloping sleeve serving as a spout, and a gravity-operated flap closure for the spout including a stationary supporting arm apertured to fit over the spout, the rim or lip portions of the spout being bent back against the arm to hold the latter rigidly, and an elongated closure flap pivotally mounted on the arm and normally resting against the rim or open portion of the spout when the receptacle is standing upright.

Still another object is the provision of a receptacle of the class described, in which the spout extrusion is formed about an axis at an angle to the horizontal, that is to say, tilted with respect to the receptacle top or closure, the spout having a gravity-operated closing flap pivotally mounted on a member wedgedly embracing the intermediate body portions of the spout.

Other novel aspects and objects of the invention, both with respect to its construction and its operation, will appear as the following description proceeds in view of the drawing, in which:

Fig. 1 is a side elevation of the cap and improved dispensing means;

Fig. 2 is a top perspective of the cap and dispensing means seen in Fig. 1;

Fig. 3 is an enlarged fragmentary sectional view through the dispensing closure means, as viewed along lines 3—3 of Fig. 2;

Fig. 4 is a bottom plan view of the dispensing closure means of Fig. 3, as viewed in the direction of lines 4—4; while

Fig. 5 is a fragmentary vertical section through the receptacle and dispensing means of Fig. 1,

showing the receptacle in substantially inverted dispensing position.

A preferred embodiment of the invention as viewed in Fig. 1 includes an upright receptacle 10 having an open top portion 11 provided with thread means or thread engaging means 12 and fitted with a substantially cylindrical metal cap 13 provided with attaching means in the form of thread engaging formations 14 which permit securing the cap to the receptacle.

The dispensing means constituting one of the objects of the invention includes a spout formation in the form of a sleeve-like portion 15 which is extruded from the cap near the edge portion thereof, or, in other words, in a position offset with respect to the center region of the cap.

Preferably, the spout formation 15 has an opening 16 which is disposed in a plane tilted at an angle to the horizontal, that is to say, tilted with respect to the plane of the top of the cap. This arrangement, together with the location of the spout close to the rim of the cap, provides for the greatest dispensing efficiency.

Automatic closing means for the dispensing spout includes a stationary supporting member 17 in the form of an elongated arm 17 (Figs. 3 and 4 particularly) having an opening formed through one particular end portion 18 thereof and embracing the intermediate sloping or conical wall portions of the sleeve spout 15, said spout having edge or rim portions 19 turned back or peened or otherwise forced against the supporting arm or member 17 so as to clamp or wedge the latter securely down against the widening slope portions of the spout sleeve.

The endwise portion 20 of the supporting arm or member 17 opposite the particular end 18 thereof, is disposed in a radial sense toward the center 21 of the cap 13 and is provided with a pair of opposite struck up ears 22 having aligned openings for mounting closure means.

Automatic or gravity-operated closure means for the spout includes an elongated flap member 23 having a pair of apertured ears 24 near one of its ends for alignment with the ears 22 on the supporting arm, there being a pintle or pivot pin means 25 extended through the openings in the several ears providing a pivotal mounting for the closure or flap member. Adjacent the inner end portion of this flap 17 is a lateral edge portion 26 which is struck up to provide a movement-limiting flange adapted to bear against the cover portion 13 when the flap or closure is open, as seen in Fig. 5, so as to regulate, in effect, the flow of granular or other material 27 from the

receptacle 10 and also to direct the movement of such material, the flap opening automatically when the spout portion is lowered and closing into the position seen in Figs. 1 through 3 when 5 the receptacle is in its normal upright position.

It will thus appear that I have provided a relatively simple dispensing closure means which may be easily and cheaply manufactured and which at the same time is rugged and efficient, 10 and while I have illustrated a preferred embodiment of the invention herein for purposes of explanation, it will be understood that the several objects heretofore declared may be achieved in other ways without departing from the spirit 15 and scope of the invention, as defined in the appended claims.

Having thus described my invention, what I claim as new and desire to protect by Letters Patent is:

20 1. A dispenser for granular substances and the like and including an upright receptacle, a top for said receptacle, a spout formed in said top by extrusion and closure means for said spout including an arm having an apertured portion embracing the spout, said spout having rim portions forced against said member to secure the latter against movement relative to the spout and a substantially planar closing flap pivotally mounted near one end on an end portion of said member 25 remote from the spout, said flap being normally disposed by gravity against the opening of the spout to close the latter when the receptacle is in upright position.

2. A dispenser including an upright receptacle, 30 a metal closing cap for said receptacle, said cap having a portion extruded to provide a spout, and closing means for the spout including an apertured arm fitted over the spout and held immovably relative to the latter by virtue of rim portions 35 of the spout being forced back against said arm, said spout being nearer the edge of said cap than the central region thereof, and closure means for the spout including a substantially elongated supporting arm having an aperture portion near 40 one end embracing said spout and having its opposite end disposed toward the central region of the cap, said spout having rim portions bent back upon said supporting arm to hold the latter rigidly, and a substantially planar and elongated 45 flap pivotally mounted at one end on said opposite end of the supporting arm, said flap having end portions opposite its pivotal mounting normally disposed by gravity against the opening of the spout when said receptacle is in an upright position.

3. A dispenser including an upright receptacle, 50 a metal cap for said receptacle and of substantially circular form, said cap having a spout portion extruded therefrom adjacent the periphery thereof, and a flap closure for said spout including a substantially elongated arm having one end portion apertured and embracing said spout, the latter having peripheral portions turned back onto said arm clamping the arm against movement with the opposite end portion of the arm directed substantially toward the center of the cap, said opposite end portion of the arm having opposite edgewise parts struck up to provide aligned ears, and a closure for said spout in the 55 form of an elongated flap member having ear

portions struck up near one end and pivotally mounted on pin means engaging said first-mentioned ears on said arm such that the opposite end portion of said elongated flap member normally gravitates against the opening of said spout when the receptacle is in an upright position. 5

4. A dispenser including an upright receptacle, a metal cap having means for removably securing the same to said receptacle, said cap having a top portion normally disposed in a substantially horizontal plane when said receptacle is in an upright position, said cap having a spout portion extruded therefrom offset from the central region thereof, said spout having a sloping intermediate body portion adjoining the cap and having an opening disposed in a plane at an angle to the horizontal, and closure means for the spout in the form of an arm having an apertured portion fitted around said intermediate portion of the spout, said spout having rim portions around 10 said opening thereof turned back upon said arm and wedging the latter immovably onto said intermediate body portions thereof, said arm having an opposite end portion extending in a radial sense toward the central portion of said cap, said opposite end portion of the arm having opposite ears struck up therefrom, and a closure flap pivotally mounted on pin means engaging said ears and normally disposed by gravity against said opening of the spout when the receptacle is in 15 upright position.

5. A dispenser including a substantially cylindrical receptacle having an open top portion and adapted normally to stand upright, and a metal cap for said receptacle and provided with thread formations for removably securing the same onto said open top portion of the receptacle, said cap having an eccentrically disposed spout formed by extruding therefrom a sleevelike formation having sloped wall portions, an elongated supporting 20 arm having a particular end portion apertured and fitted over said sloping portions of the spout formation, said spout having rim portions peened back onto the supporting arm and forcing the latter rigidly against the wider sloping portions 25 of the spout formation, said supporting arm having its inner end portion opposite the said particular end thereof directed in a radial sense toward the center of the cap, said inner end portion of the arm having opposite ears struck up thereon, and an elongated closing flap for the spout having opposite ear portions struck down near one end thereof and pivotally mounted on said supporting arm by pin means extending through 30 said ears, the opposite end portion of said flap normally resting against said rim portion of the spout and closing the latter when said receptacle is in upright position, said flap automatically opening when said receptacle is tilted to lower 35 said spout portion.

6. A dispenser constructed in accordance with the provisions of claim 5 and in which said closing flap is additionally provided with an offset formation in the region of its pivotal mounting on said supporting arm for the purpose of limiting 40 the opening movement of the flap when said receptacle is tilted out of said normal position such that said flap will be urged toward fully open position.

SAMUEL BLOOMFIELD. 70
